UNITED STATES PATENT OFFICE

ALFRED HERSLER BORGQVIST, OF COPENHAGEN, DENMARK

GRAMOPHONE, MEGAPHONE, OR THE LIKE

Application filed May 31, 1928, Serial No. 281,938, and in Denmark September 6, 1927.

This invention relates to improvements in horns for gramophones or other devices for receiving or emitting music, speech and other sound vibrations, in order to obtain a great 5 energy of the sound vibrations passing said horns or trumpets or rather to avoid any diminishing of the original sound energy and to absorb over-tones and other disturbing vibrations.

10 This can certainly also be obtained by making the trumpet-walls very substantial, but if they are so, their vibrations will at the same time become less lively, and this can only be avoided by enlarging the measurements of the trumpet to such an extent that it would become practically inapplicable.

15 The purpose of my invention is to produce a horn possessing the advantages of the last mentioned construction without having its great dimensions and substantial walls. This is effected by making the walls which are chiefly designed to reproduce the original vibrations of the source of sound not more substantial than is usually the case, but firstly 20 to apply outside the trumpet some devices partaking of the vibrations of said walls, secondly a heavy load as a resistance against too lively vibrations of said walls.

25 A still better result can be obtained by arranging some vibrating walls or other vibrating elements inside the horn. By using such co-vibrating elements and those mentioned above, the single voice of the instrument will in some way be replaced by a chorus of several voices which are absolutely 30 harmonious and nevertheless differ from them by their ability to reproduce the original vibrations in different clang-tints and therefore also are able to better reproduce 35 the particularities of different instruments or voices.

40 By this construction it also becomes possible to absorb not only all superfluous over-tones and to subdue the murmur of the high-speed gears of motors or the like, to avoid rumbling, rushing, snoring and crepitating sounds, but also at the same time to magnify the sound of the instruments in a surprising degree.

45 The accompanying drawing shows some

devices as examples for practising my invention.

Fig. 1 represents one feature of a gramophone horn in a vertical section,

Fig. 2 the same in front-elevation on a lesser scale,

Fig. 3 and 4 two other features of gramophone horns, both in vertical sections.

The horn 1, preferably of a saxophonelike shape, is for instance by a flange 24, fastened 50 to the bottom 2 of the disc-room 25 and by a ring shaped piece 3 connected with a plate or tongue 4 of metal, f. i. bronze or steel. This plate may be connected with one or several other plates 5 and with the sound board 6 by a bolt 7, or in any other way. Said metal plates 4 and 5 are suspended by the elements 3 and 7 only. Between each pair of metal plates 4 and 5 and between the last metal plate 5 and sound board 6 fastened at its sides 55 and below to the case 11 of the machine, there are provided spacing rings, elements or washers 8, 9 and between the sound board and the rear-wall of the case a spring 12 may be inserted in order to keep said sound board 60 at a certain tension and thus to cause a re-sounding connection between the plate 6 and the outer wall 11 of the case.

65 As the upper and lower walls of the horn are very thin but comparatively broad, and thus their vibrations could become too lively, there is in the bow of the horn provided a weight 14 of any kind, preferably moulded of gypsum, concrete, or other plastic and later on hardening material. This weight 70 will partake in the vibrations, thus reducing them to a strength which is more applicable to their purpose.

75 Another shape of the horn is shown in Fig. 3. Inside the mouthpiece of the horn there is inserted another but smaller horn 15 partaking in the vibrations of the outer horn 1. Thus the room of the main-horn is divided into three smaller rooms 16, 16, 16, and the area of vibrating elements essentially increased.

80 The construction of the apparatus differs also in other ways somewhat from that shown in Fig. 1. The metal plate 4 is in Fig. 3 directly connected with the outside of the 85

horn 1, and the transfer of the vibration to the following metal plate 5 or -plates, is effected by a screw 8^a with a nut 8^b connected with the plate. In this case it is advisable to divide the sound board into two parts and connect the plate 5 by bolts with each of these parts. Also in this case springs 12 are applied to hold said sound boards in tension.

10 Instead of or together with the inner horn 15 there may be inserted metal tongues 23 being connected with the rigid side walls of the horn 15 at one point 22 only and eventually also tongue-shaped metal pieces 19, 19, 15 21 inside the neck of the horn. The last one is suspended at one point 20 only, meanwhile the pieces 19 are fastened to the side walls of the neck.

15 The two types of horns just specified are generally connected with the outer system of vibrating elements 4, 5, 6, and 11, as named in connection with Figs. 1 and 2.

What I claim is:

1. In sound amplifying apparatus, a horn 25 formed with a sharp goose-neck bend, in combination with a heavy mass disposed exteriorly of said horn between and engaging the opposing inner walls of said sharp bend thereof and serving to dampen the vibrations of the walls of said horn.

2. In sound amplifying apparatus, a horn 35 formed with a sharp goose-neck bend, and a sound board, in combination with a plurality of resonance plates, one of said resonance plates being mounted on said horn in spaced relation thereto to receive vibrations from the wall thereof, and another of said resonance plates being mounted on said sound board in spaced relation thereto, and an adjusting screw mounted in the latter resonance plate and adjustable therethrough to engage and exert varying degrees of pressure on the resonance plate mounted on the horn.

3. In sound amplifying apparatus, a horn 45 formed with a sharp goose-neck bend, resounding elements disposed exteriorly of said horn and mounted to receive vibrations direct from a wall of said horn, and a heavy mass disposed exterior of said horn and filling the interval between the opposed inner walls of said goose-neck bend thereof and serving to dampen the vibrations of the walls of said horn.

4. In sound amplifying apparatus, a horn 55 formed with a sharp goose-neck bend, a sound board, a plurality of resonance plates, one of said resonance plates being mounted on said horn in spaced relation thereto to receive vibrations from the wall thereof, another of said resonance plates being mounted on said sound board in spaced relation thereto, and an adjusting screw mounted in the latter resonance plate and adjustable therethrough to engage and exert varying

degrees of pressure on the resonance plate mounted on the horn, in combination with means located between the opposing external faces of the inner opposing walls of the sharp goose-neck bend of said horn and simultaneously engaging said walls to dampen the vibrations of the walls of said horn.

5. In sound amplifying apparatus, a horn 70 formed with a sharp goose-neck bend, a support, a sounding board mounted at one end on said support, and a spring interposed between said support and the other end portion of said sounding board and forcing the latter away from said support, in combination with a plurality of resonance plates, 75 one of said resonance plates being mounted on said horn in spaced relation thereto to receive vibrations from a wall thereof, and another of said resonance plates being mounted on said sounding board in spaced relation thereto, and an adjusting screw 80 mounted in the latter resonance plate and adjustable therethrough to engage and exert varying degrees of pressure on the resonance plate mounted on the horn.

90 In testimony whereof, I have signed my name to this specification at Copenhagen this sixteenth day of May, 1928.

ALFRED HERSLÉB BORGQVIST.
